Primary Examiner — Mary Ann Calabrese*Assistant Examiner* — Catherine Ho(74) *Attorney, Agent, or Firm* — Dickinson Wright PLLC(57) **CLAIM**

The ornamental design for a mobile showroom, as shown and described.

DESCRIPTION

FIG. 1 is a perspective view of a mobile showroom, showing our new design;

FIG. 2 is another perspective view thereof;

FIG. 3 is a side elevation view thereof;

FIG. 4 is the opposite side view thereof;

FIG. 5 is a top view with canopy removed for clarity of disclosure thereof;

FIG. 6 is a front elevation view thereof;

FIG. 7 is a rear elevation view thereof; and,

FIG. 8 is a top view thereof.

In the drawings, the broken lines depict environmental subject matter that forms no part of the claimed design.

1 Claim, 8 Drawing Sheets(56)
